ATTORNEY

UNITED STATES PATENT OFFICE.

WILLIAM WITCUFFSK, OF OKOTOKS, ALBERTA, CANADA.

LEG-PROTECTING DEVICE FOR CATTLE.

Application filed November 30, 1925. Serial No. 72,384.

The object of this invention is to provide special means for protecting cattle against the annoyance occasioned by the so-called heel fly which is prevalent in sections of the 5 United States and Canada, and which produces results causing serious loss to stock raisers.

A further object is to provide a device of the type indicated, which shall include 10 an element to be passed around the leg and which is adapted to be retained by a projecting element or strap end, and a buckle, this portion of the device being reinforced by a metallic element serving to keep the 15 protector in correct position.

A further object is to provide a device including the structure indicated, and further including defending portions movable freely about the heel of the animal, and adapted to 20 serve the purpose intended, that is to prevent annoyance by the particular type of insect specified.

With the foregoing and other objects in view, the invention consists in the novel construction and arrangement of elements described, illustrated and claimed, it being understood that modifications may be made 25 within the scope of the claim, without departing from the spirit of the invention.

30 In the drawings forming part of this application,

Figure 1 shows the device in elevation, and in operative position.

Figure 2 is a perspective view showing the 35 securing devices unattached, and showing in dotted line various elements of construction referred to in detail below.

The upper and lower portions of the structure being described may if desired be

formed integrally, so far as the leather or 40 fabric portion is concerned, and in the first instance, I have shown an upper portion 10, which is folded over, to form an inner thickness 11, constituting in a sense a leg guard or protecting device, the outer portion 10 including the defending strips so formed by 45 slotting or slitting the leather vertically to provide a plurality of tongues or the like, which are movable freely about the ankle of the animal, for the purpose specified. 50

The extension, or strap 13 is provided with apertures 14, and the strap is engaged by buckle 15 secured to the end portion 16 of the upper element 10.

Within the inner guard portion 11, or between the latter and the outer portion 10, I provide a reinforcing element 16, which may be of wire of suitable gage, and which may also be resilient, the element 16 serving to hold the encircling member in close contact 55 with the leg of the animal and in correct position. The element 16, forms in a sense a split ring, and tends to shape the device with reference to the leg, in order to maintain the correct position indicated. 65

What is claimed is:

A device of the class described, comprising a leg encircling portion having an inwardly turned portion forming a guard, a reinforcing device, of resilient material, between said 70 guard and the portion first named, securing means for said leg encircling portion, and devices freely depending from said portion last named.

In testimony whereof I affix my signature. 75

WILLIAM WITCUFFSK.
